7 Claims. (Cl. 179—171)

This invention relates to a circuit arrangement for amplifying electric oscillations, more particularly oscillations having a wavelength of less than 10 meters.

In the drawing, Fig. 1 shows a known circuit arrangement which will serve to explain the present invention, and Figs. 2, 3 and 4 are circuits which illustrate two embodiments of the present invention.

The known amplifier arrangement of Fig. 1 comprises a discharge tube 1 having a cathode 2, a control grid 3, a screening grid 4 and an output electrode 5, the screening grid 4 being given a high positive bias and the output electrode 5 a feeble positive or negative bias. Intermediate the control grid 3 and the cathode 2 there is provided an input impedance 6 to which the oscillations to be amplified are fed, whereas the output electrode 5 and the cathode 2 have interconnected between them an output impedance 7 from which the amplified oscillations are derived.

The operation of this known circuit is based on the fact that intermediate the screening grid 4 and the output electrode 5 is formed a space charge whose density is governed by the alternating voltage active at the control grid. This space charge induces in the output electrode a corresponding positive image charge whose intensity depends on the alternating voltage operative at the control grid and gives rise to the occurrence of an amplified voltage across the output impedance 7.

When oscillations having a wavelength below 10 meters are amplified this circuit arrangement has the disadvantage that a virtual ohmic resistance of comparatively low value occurs between the output electrode 5 and the cathode 2 and gives rise to a heavy damping of the output circuit. This heavy output damping renders the relevant circuit arrangement less suitable for the amplification of ultra-high frequencies.

According to the invention, this disadvantage is obviated by the use of a perforated output electrode and by the arrangement of one or more electrodes on which a positive bias is placed on that side of the output electrode which is remote from the cathode.

The invention is based upon recognition of the fact that by reason of the use of a perforated output electrode and beyond it of a positive electrode the output damping is considerably reduced and may even become negative.

In order that the invention may be more clearly understood and readily carried into effect it

will now be described more fully with reference to Figs. 2 and 3.

The circuit arrangement shown in Fig. 2 is differentiated from the known arrangement shown in Fig. 1 in that the output electrode 5 which, similarly to the arrangement shown in Fig. 1 is given a negative bias, is constructed in the shape of a grid and beyond it is arranged an electrode 8 which is earthed so far as high frequencies are concerned through a condenser 9 and to which a positive bias is supplied through a resistance 10.

Thus, a materially lower damping than in the known circuit arrangement occurs between the output electrode 5 and the cathode 2 and this damping may even be rendered negative by a suitable choice of the bias of the output electrode 5. It is obvious that this renders possible considerably greater amplification of ultra-high frequency oscillations than can be obtained in the known arrangement.

The occurrence of a negative output damping in the arrangement shown in Fig. 2 may be due to the following. If a high negative bias is applied to the electrode 5 all the electrons passed by the screening grid 4 will reverse their direction before the electrode 5. The reversing electrons form a space charge in front of the electrode 5 which induces a corresponding positive image charge in the electrode 5. If the bias of the electrode 5 is rendered less negative, then a part of the arriving electrons will be passed by the electrode 5 so that the said space charge is reduced and consequently a lower positive charge occurs in the electrode 5. There is consequently a range of biases of the electrode 5 in which the charge of this electrode becomes less positive if the bias is rendered more positive. In this range the electrode 5 has therefore a negative capacity relatively to the cathode so that if an alternating voltage is applied to the electrode 5 a current will flow to the cathode which lags by 90° with respect to the voltage. This current is transmitted by the electrons which flow from the cathode to the space charge occurring in the neighbourhood of the electrode 5. In the case of ultra-high frequencies the transit time of the electrons from the cathode to the space charge will be of the same order of magnitude as the period of the oscillations to be amplified so that the transmission of the said current will be effected with a noticeable time lag. The current will thus manifest a greater lag than 90°, i. e., it will contain a component which is in antiphase with the voltage applied to the electrode. This component

brings about the said negative output damping.

The current flowing through the electrode 5 to the positive electrodes arranged beyond it will be governed by the amplified alternating voltage occurring at the electrode 5. This may be taken advantage of by arranging for the circuit of one of the positive electrodes situated beyond the electrode 5 to include a second output impedance across which a doubly amplified voltage will occur. This method permits of obtaining very high amplification of ultra-high frequencies by means of a single tube.

One example of this embodiment of the invention is shown in Fig. 3. The electrode 8 is constructed as a screening grid and beyond it is arranged an anode 11 which is connected to the cathode with the interposition of an oscillatory circuit 12 tuned to the frequency of the oscillations to be amplified. The singly amplified voltage across the circuit 7 is amplified once more in the part of the tube formed by the electrodes 5, 8 and 11 so that a double amplified voltage can be derived from the circuit 12. In this circuit arrangement use may be made of a hexode, a pentagrid or an octode of the usual type, the oscillations to be amplified being fed to the first control grid, the circuit of the second control grid whose negative bias is preferably such that a negative resistance occurs between this control grid and the cathode including an oscillatory circuit tuned to the frequency of the oscillations to be amplified and the doubly amplified output voltage being obtained from the anode.

The circuit arrangement shown in Fig. 3 may be used as a mixing stage in a superheterodyne receiver. For this purpose, as shown in Fig. 4 which is the same as Fig. 3 except for the portion to the right of the dash line x-x, the circuit of the electrode 5 includes, for example in series with the circuit 7, an impedance 13 across which there is impressed the locally generated oscillations from a source 14 and the circuit 12 is tuned to the intermediate frequency.

We claim:

1. A circuit arrangement for the amplification of ultra-high frequency oscillations, comprising an electron discharge tube having at least a cathode, a control grid, a screen grid, a perforate output electrode and one or more additional electrodes disposed in the order named, means for impressing a high positive bias on the screen grid and the one or more additional electrodes, and means for impressing a negative or low positive bias on the output electrode.

2. A circuit arrangement as defined in claim 1, wherein the bias of the perforate output electrode is such that a negative resistance occurs between said output electrode and the cathode.

3. A circuit arrangement for the amplification of ultra-high frequency oscillations, comprising an electron discharge tube having at least a cathode, a control grid, a screen grid, a perforate output electrode and at least one additional electrode disposed in the order named, an input cir-

cuit connected between the control grid and cathode, means for impressing a high positive bias on the screen grid and said additional electrode, an output circuit connected between the perforate output electrode, and means for impressing a negative or low positive bias on said output electrode.

4. A circuit arrangement as defined in claim 3, wherein the input and output circuits are resonant circuits tuned to the frequency to be amplified, and the additional electrode disposed on the side of the output electrode remote from the cathode is connected to ground with respect to high frequencies.

5. A circuit arrangement for the amplification of ultra-high frequency oscillations, particularly oscillations having a wave length less than 10 meters, comprising an electron discharge tube having at least a cathode, a control grid, a screen grid, a perforate electrode, a second screen grid and an imperforate output electrode disposed in the order named, a first resonant circuit connected between the control grid and cathode, a second resonant circuit connected between the perforate electrode and cathode, a third resonant circuit connected between the imperforate output electrode and cathode, the first and third circuits constituting respectively the input and output circuits and all three resonant circuits being tuned to the frequency of the oscillations to be amplified, means for impressing a high positive bias on the screen grids and the imperforate output electrode, and means for impressing a negative or low positive bias on the perforate electrode.

6. A circuit arrangement as defined in claim 5, wherein the circuit of the perforate electrode includes an impedance across which are developed locally generated oscillations of a frequency differing from the frequency of the oscillations to be amplified, and the output circuit connected to the imperforate electrode is tuned to the difference or intermediate frequency.

7. A circuit arrangement for the successive amplification of ultra-high frequency oscillations, particularly oscillations having a wave length less than 10 meters, comprising an electron discharge tube having arranged in the order named at least a cathode, a control grid, a screen grid, a perforate electrode, a second screen grid and an imperforate output electrode, an input circuit tuned to the frequency of the oscillations to be amplified connected to the control grid, second and third circuits tuned to the same frequency as the input circuit connected respectively to the perforate and imperforate electrodes, means for impressing a high positive bias on the screen grids and the imperforate output electrode, means for impressing a negative or low positive bias on the perforate electrode, and means for connecting the screen grids to ground with respect to said high frequency oscillations.
